(57) **CLAIM**

The ornamental design for a hair clip as shown and described.

DESCRIPTION

FIG. 1 is a left, front, bottom perspective view of a hair clip of my new design;

FIG. 2 is a bottom plan view thereof;

FIG. 3 is a front elevational view thereof;

FIG. 4 is a top plan view thereof;

FIG. 5 is a rear elevational view thereof;

FIG. 6 is a left side elevational view thereof;

FIG. 7 is a right side elevational view thereof; and,

FIG. 8 is a left, rear, bottom perspective view thereof.

The broken lines in the drawings depict portion of the hair clip that form no part of the claimed design.
